GUSTAV EGLOFF AND LEV A. MEKLER, OF CHICAGO, ILLINOIS, ASSIGNORS TO UNIVERSAL OIL PRODUCTS COMPANY, OF CHICAGO, ILLINOIS, A CORPORATION OF SOUTH DAKOTA

METHOD AND APPARATUS FOR UTILIZING RADIANT HEAT ENERGY

Application filed June 21, 1928. Serial No. 287,303.

The present invention relates to improvements in distributing the application of radiant heat to heat absorbing surfaces, and deals particularly with the heating of liquids in tubular heaters, such as boilers, stills and the like.

This invention relates more specifically to the use of radiant heat reflecting surfaces in the proximity of the original source of radiant energy to distribute the radiant heat emanating from the original source of radiant energy onto the main body of the tubes absorbing the heat. This invention broadly contemplates reflecting surfaces either totally or partially surrounding the tube bank.

Since the reflecting power of a surface is a function of the color of the surface and its brightness, and since the brightness diminishes for the same surfaces with increase of temperature, this invention contemplates cooling the radiant heat reflecting surfaces to maintain the surfaces at their maximum reflecting power. The fluid being heated in the main body of the tube bank, or any other auxiliary fluid, may be used as the cooling medium for the radiant heat reflecting surfaces.

In a companion application, Serial No. 287,302, filed June 21, 1928, we propose to construct the tubes in such a manner that these tubes through which the liquid is passed will thus function, in varying degrees, as radiant heat reflecting surfaces. In that application we propose to accomplish the invention by making tubes closest to the source of radiant heat energy of greater radiant heat reflecting power than the tubes further away from the source of radiant heat, and in the preferred form of the invention, the radiant heat reflecting power of the tubes progressively decreases in a direction away from the source of radiant heat energy, the heat absorbing power of such tubes becoming progressively greater as the heat reflecting power progressively diminishes.

The present invention contemplates the use of heat reflecting surfaces which are not used for the heating of liquid therein, and the concept of the invention may be used alone or in combination with the concept

described in said application, Serial No. 287,302, filed June 21, 1928.

The utility of the invention as well as objects and advantages thereof will be more apparent from the following description:

The single figure in the drawing is a diagrammatic vertical sectional view of a furnace equipped to carry out the present invention.

Referring more in detail to the drawing, 1 designates a furnace provided with the heat generating chamber 2 and tube chamber 3. Products of combustion are generated in the heat generating chamber 2 through the medium of the burners diagrammatically illustrated at 4, said products of combustion passing up through the flues 5 in the bridge wall 6 into the upper portion of the tube chamber 3. The spent products of combustion are removed through the flue 7, which communicates with a suitable stack (not shown).

In the upper portion of the tube chamber 3 may be disposed a metal shell 8, the surface of which is so constructed as to function as a heat reflecting means whereby radiant heat energy is reflected onto the tube bank 9. For this purpose the shell may have applied thereto a coating of material possessing high radiant heat reflecting power, or the shell 8 may contain as manufactured ingredients which normally result in a surface having high radiant heat reflecting properties. For instance, the shell 8 may be plated with chromium, nickel chromium or the like, or may be constructed of stainless steel or ascaloy and may be subsequently polished.

As pointed out heretofore, the upper row or rows of tubes may be so constructed as to function as heat reflecting surfaces almost entirely, the heat reflecting power of said tube surfaces progressively diminishing in a direction downward through the tube bank, while the heat absorbing power progressively increases in direct relation to the decrease of heat reflecting power.

As a feature of the present invention, heat reflecting surfaces 10, 11 and 12 may be disposed adjacent the tube bank 9 in such a manner as to reflect the radiant heat into the

tube bank. It is to be understood that while we have diagrammatically illustrated the radiant heat reflecting surfaces 10, 11 and 12 as being round and rectangular, respectively, it is to be understood that this is merely diagrammatic and these surfaces may take any desired form. These surfaces 10, 11 and 12 are preferably hollow so as to permit the passage therethrough of a cooling medium. It 10 will be recalled, as we pointed out heretofore, that the heat reflecting power of a surface is directly related to its brightness or dullness, and since it is well known that heat will dull a surface, we contemplate the introduction of 15 a cooling medium into and through the radiant heat reflecting surfaces 10, 11 and 12 to maintain these surfaces at a desired brightness.

It is to be also understood that while we 20 have illustrated the heat reflecting surfaces 10, 11 and 12 as surrounding the tube bank 9 on three sides, that this is also merely illustrative to show the concept of the invention. The invention contemplates that the 25 heat reflecting surfaces illustrated at 10, 11 and 12 will be disposed relative to the tube bank 9 in such a manner as to most efficiently utilize the radiant heat energy available.

The products of combustion from which 30 the total heat (both convection heat and radiant heat) is obtained maintain the refractories of the furnace, if the same are used in place of the element 8 at incandescent temperatures, and these refractories act as 35 the original source of radiant heat energy. In utilizing the shell 8 the radiant heat reflected by said shell from the combustion chamber 2 will act in a similar manner to a source of radiant heat energy. The portion 40 of the radiant heat energy striking the reflecting surfaces 10, 11 and 12 will be reflected from these surfaces toward the main bank of tubes 9 so that aside from the tubes usually exposed to the usual source of radiant heat 45 energy, additional tubes within the tube bank will obtain reflected or reradiated radiant heat energy.

By the present invention it is possible to 50 subject to the action of radiant heat a larger portion of a tube bank and to apply the radiant heat much more uniformly throughout a greater portion of the tube bank than is possible in other types of construction.

55 We claim as our invention:

1. A method of distributing the application 60 of radiant heat to heat absorbing surfaces, which comprises maintaining an original source of radiant heat energy, disposing heat reflecting surfaces in the proximity of the original source of radiant heat energy and thus distributing the radiant heat emanating from such original source to predetermined heat absorbing surfaces through the medium 65 of said reflecting surfaces, and cooling said

reflecting surfaces to maintain same at maximum reflecting power.

2. In combination with an element to be heated and an original source of radiant heat, of heating reflecting surfaces in proximity 70 to said original source and adapted to distribute radiant heat from said original source to said element, and cooling means for said heat reflecting surfaces.
